UNITED STATES PATENT OFFICE.

FREDERICK CALLARD, OF BROOKLYN, NEW YORK.

DESIGN FOR A CAKE.

SPECIFICATION forming part of Design No. 23,875, dated December 11, 1894.

Application filed August 22, 1894. Serial No. 521,038. Term of patent 3½ years.

To all whom it may concern:

Be it known that I, FREDERICK CALLARD, a citizen of the United States, residing at Brooklyn, in the county of Kings and State of New York, have invented and produced a new and original Design for Cakes, of which the following is a specification.

The leading feature of my design, which is shown in the accompanying drawings, consists in a cake with curved periphery and with a panel in the center of the upper surface of the cake, which surface is divided into four nearly equal spaces striated by parallel lines radiating from the central panel and leading to the circumference of the cake.

Figure 1 is a top plan view. Fig. 2 is a linear, vertical section.

A is the center of the cake with a smooth

ground and serving as a panel, upon which the name of the cake may be impressed.

B is the periphery of the cake, which is composed of regular curves, so as to form a symmetrical outline.

The space between the periphery B and the panel A is covered with lines radiating from the center in such a way that the cake is marked off into four parts striated with parallel lines, as shown.

I claim—

The design for cakes herein shown and described.

FREDERICK CALLARD.
